UNITED STATES PATENT OFFICE

140,754

DESIGN FOR A TEAKETTLE

James H. Reichart, Muncie, Ind.

Application November 23, 1944, Serial No. 116,506

Term of patent 14 years

(Cl. D44—25)

To all whom it may concern:

Be it known that I, James H. Reichart, a citizen of the United States and a resident of Muncie, county of Delaware, and State of Indiana, have invented a new, original, and ornamental Design for a Teakettle, of which the following is a specification, reference being had to the accompanying drawing, forming part thereof.

In the drawing:

Fig. 1 is a top plan view of a teakettle showing my new design, and

Fig. 2 is an edge elevational view thereof.

The dominant feature of my design resides in the portion disclosed in full lines.

I claim:

The ornamental design for a teakettle, as shown and described.

JAMES H. REICHART.
